UNITED STATES PATENT OFFICE.

WILLIAM A. CASWELL, OF CHICAGO, ILLINOIS, ASSIGNOR TO NATIONAL DUMP CAR COMPANY, A CORPORATION OF MAINE.

DUMP-CAR AND DOOR-OPERATING MECHANISM.

1,107,896.

Specification of Letters Patent. Patented Aug. 18, 1914.

Application filed January 14, 1907. Serial No. 352,195.

To all whom it may concern:

Be it known that I, WILLIAM A. CASWELL, a citizen of the United States, residing at Chicago, in the county of Cook and State of Illinois, have invented certain new and useful Improvements in Dump-Cars and Door-Operating Mechanism, of which the following is a specification.

The object of my invention is to provide improved means for operating the doors of dump cars, and more particularly to provide means whereby any one or more of the doors may be unlocked and opened independently of the others, as well as to provide a new and improved center sill especially adapted for use with door-operating mechanism herein described, but also useful in connection with other door-operating mechanism and in cars not provided with dumping doors.

Referring now to the drawings—Figure 1 is a cross section of a car constructed in accordance with my invention showing one pair of doors, one of the doors being closed and locked and the other in its lowered or open position. Fig. 2 is a view similar to Fig. 1, but showing a modified form of gearing for closing the doors. Fig. 3 is a side view of a portion of a car showing the mechanism at the end of the car, the operating mechanism for one of the doors, and part of that for the adjoining door. Fig. 4 shows in section the telescoping shafts for operating the door-locking mechanism and the links connected thereto. Fig. 5 is a transverse section showing the construction of one of the transverse beams and part of the sides of the car. Fig. 6 is a sectional view, taken on line 6—6 of Fig. 5 looking in the direction of the arrow. Fig. 7 is a sectional view, taken on the line 7 of Fig. 5 looking in the direction of the arrow. Fig. 8 is a section, taken on the line 8 of Fig. 5 looking in the direction of the arrow. Figs. 9, 10 and 12 are detail views of the locking members 2, some of the parts being shown in section. Fig. 11 is a sectional detail view of one of the locking members 20. Figs. 13 and 14 are detail views of one of the door-operating arms 12; and Fig. 15 represents another form of locking member.

I have illustrated my invention in connection with dumping doors 9 connected at the center of the car by a flexible plate 42, of

steel or other suitable material. The inner edges of the doors are connected by the links 43, 45 to the center sill of the car, and at the center of the car there is sufficient clearance between the inner edges of the doors to embrace the member 40 of the center sill. Inasmuch as my invention claimed herein is applicable to doors hinged to the car body in any suitable manner, further description of the particular means illustrated for that purpose is unnecessary.

Power for raising the doors is applied by means of the hand wheel 61, bevel gear 62, vertical shaft 63, worm gears 64, 65, arm 12, and roller 15 operating on the track 78 fixed to the underside of the door 9—all shown in Fig. 1 of the drawings. The arm 12 comprises two parts, 13 and 14, connected to each other by the pivot 66. The lower member 14 is recessed at its upper end, as shown in detail in Figs. 13 and 14, and the upper member is pivoted within the recess. The lower face of the recess is inclined, as shown at 69, and a corresponding inclination is formed on the lower end of the member 13.

By this construction the upper member 13 is permitted to turn to the right on the pivot 66 from the position shown in Figs. 13 and 14, but is prevented from turning to the left by the contacting faces 68 and 69, and also by the bridge 67 extending between the two prongs of the upper end of the part 14. By means of this construction the doors are rigidly supported when the parts are in the position shown in connection with the door on the left-hand side of Fig. 1 of the drawings. The doors are raised by applying power to the arm 12, through the hand wheel 61 and connected gearing. When the door is raised to a horizontal position, the roller 15 on the arm 12 enters the notch 115 in the track 73. In lowering the doors, any difficulty which might otherwise arise from the weight on the door holding the roller 15 in the notch 115 is avoided by the pivotal connection between the members 13 and 14 of the arm 12. When the hand wheel 61 is turned in the proper direction to lower the door, the members of the arm 12 will turn upon the pivot 66, until the roller 15 is released from the notch referred to.

It will be understood that the numerals 9 each represent a series of doors extending longitudinally of the car, there being one

row of doors on each side of the center. The doors may be hinged either at the center of the car, as shown, or along the sides—my invention as described herein being equally applicable to either type of car.

The shafts 16 upon which the door-operating arms 12 are mounted, extend preferably half the length of the car,—one of the arms 12 being located adjacent each edge of each door. By means of this construction half of the doors on one side of the car may be closed at once, by applying power to one of the shafts 16. It is to be observed, however, that when the shafts 16 are operated to lower the arms 12, the doors will not open until unlocked.

As above stated, one of the principal features of my invention is to provide improved locking means for the doors, whereby any one or more of them may be unlocked and permitted to open independently of the others. This feature of my invention is of great value where it is desired to discharge part of the contents of a car into a wagon or elsewhere and leave the remainder of the contents undisturbed. The mechanism by which this is attained will next be described.

Located beneath the car are a series of tubular telescopic shafts 55, 56, 57 and 58 extending longitudinally of the car, these shafts increasing in length as their diameter decreases. The largest shaft 58 is connected through the mechanism described below to the locking devices of the door nearest the end of the car, and extends from the end of the car substantially to the inner edge of the first door. The shaft of next smaller size projects beyond the larger shaft a distance substantially equal to the width of the second door, and each of the remaining shafts projects a corresponding distance beyond the shaft next larger in size. The projecting parts of each of the shafts 55, 56 and 57 are connected to the locking mechanism of the doors located above such projecting parts.

The ends of the tubular shafts 55—58 project beyond the end of the car a sufficient distance for the attachment of the crank arms 49, 52, 53 and 54. The operating hand levers 46, 70, 71 and 72 are connected to the crank arms by means of links, as shown. When the levers are raised they occupy a substantially vertical position adjacent to the vertical plate 100, which extends outwardly from the end wall of the car, and is affixed thereto by angle irons or other suitable means. Means are provided upon the plate 100 for holding the levers 46 in upright position and thus preventing the doors from being unlocked. These means may consist simply in links 60 secured to rings in the plate 100, as shown in Fig. 1, or a retaining plate or bar may be pivotally or slidably secured to the plate 100 and means provided whereby such plate or bar may be locked

in position, for the purpose of preventing unauthorized persons from unlocking the doors. By means of the mechanism above described, it will be obvious that any of the tubular shafts may be rotated independently of the others.

Secured to each of the tubular shafts are two cranks 80. Links 1 are pivotally connected to these cranks and extend outwardly therefrom, approximately to the side of the car, where they are pivotally connected to the locking members 2. These locking members are shown in detail in Figs. 9, 10 and 12, and are pivoted on their upper ends on the stationary shafts 30, each of which is of a length substantially equal to the width of one of the doors. The shafts 30, may, however, run throughout the length of the car, if so desired.

Each locking member consists of two plates of sheet metal 91 and 92, secured together and bent into the form illustrated, thus forming bearings for the anti-friction rolls 3 and 4, and also embracing the block 5, which is secured thereto by rivets or otherwise. The anti-friction rolls 3 bear upon the projections 7 of the transverse beams 93 when the doors are in closed position, as shown at the left-hand side of Fig. 1, and the rolls 4 engage the under sides of the doors and hold them in closed position. The locking members may be moved from the position shown at the left-hand side of Fig. 1 to that shown at the right-hand side by lowering the hand lever 46, the movement of which is communicated to the locking members through the links 50, cranks 80, tubular shafts 55, 56, 57 and 58, crank arms 80 and links 1.

It will be understood from the foregoing description that each of the levers 46, 70, 71 and 72 is connected through the tubular shaft secured thereto to the locking mechanism of one only of the doors, and that means are thus provided for unlocking any one or more of such doors. Preferably, the locks of half of the doors on one side of the car are operated by one set of levers and the connected tubular shafts, the smallest of the tubular shafts 55 extending half the length of the car. There will thus be two sets of operating levers at each end of the car by which half of the doors on either side of the center may be locked and unlocked. For convenience in manipulating the doors, I prefer to number each door,—placing the number on the side of the car above the door—and to number each of the lock-operating levers correspondingly. The numbers for the levers may be placed on the plate 100.

The auxiliary locking members 20 are secured to the plates 95, to which the main locking members 2 are also secured. Each of the plates 95 extends throughout the width of one of the dumping doors, and

through the plates 95 all of the locking members are caused to move in unison. This plate also serves as a continuation of the side of the car and protects and conceals the 5 door-locking mechanism from view.

The numeral 96 represents angle irons secured in the channel iron 31, to guide and retain the locking members 2 and 20 against displacement.

10 In Fig. 3 of the drawing I have shown the door nearest the end of the car with the plate 95 removed. In connection with the adjoining door the plate 95 is shown in proper position.

15 The numeral 31 represents a U-shaped or channel member extending along the lower edge of the side of the car, and 21 represents a plate fixed on the outer surface of the side of the car and projecting at its lower edge 20 slightly below the upper edge of the cavity formed by the member 31. The fixed bearing rod 30 of the locking members extends longitudinally of the channel within the member 31.

25 The modified form of gearing illustrated in Fig. 2 differs from that described, merely in the manner of transmitting power from the hand wheels to the shaft 16. In the modified form I have shown a sprocket 30 chain 97 engaging a sprocket wheel 98 secured to the hand wheel shaft and running over the idler 96, loosely mounted on one of the tubular shafts and engaging teeth 99 upon the segment 65. It will be understood 35 that my invention is not restricted to any particular manner of transmitting power from the hand wheel to the power shaft 16, but that any suitable mechanism may be employed for this purpose without departing 40 from the scope of my invention.

In Figs. 5, 6, 7 and 8 I have illustrated the structure of the underframe of the car as adapted for use in connection with the other features of my invention, as described 45 above. In many particulars, however, the structure of the underframe illustrated in these figures is equally adapted for use in 50 exs not embodying my improved door-operating mechanism. In these views the numeral 93 represents the main web of one of the transverse beams. I-beams 40 and 44, together with the horizontal stiffening plate 43, secured between them, constitute the center sill of the car. The part 41 is a saddle 55 having a curved surface, provided for the purpose of causing the flexible plate 42—referred to above—to bend in a gradual curve, thus avoiding the danger of fracture. The members 41 are preferably of a length equal 60 to the width of the doors between which they are located. The I-beam 40 and stiffening plate 43 may extend continuously throughout the length of the car.

The main web 93 of the transverse beam 65 is reinforced at its upper edge by angle

irons 105, which are secured to and contact with such web, except at the end portions, where they are bent outwardly and spaced from the web 93. The plates 104, as shown in Fig. 8, extend from a point above the 70 floor of the car, where they are secured to the side stakes, through the space between the angle irons 105 and the web 93. Below the angle irons 105 the plates 104 are bent outwardly, forming openings 110 between 75 said plates and the web 93, said openings being for the purpose of supporting and guiding the levers 1 of the locking mechanism.

Plates 104 are secured to the web 93 by 80 rivets, and these plates have projecting portions 7, above referred to, upon which the lower rolls of the locking members rest when the doors are locked. In order to strengthen the web 93 of the transverse 85 beam and to provide suitable bearings for the tubular shafts of the locking mechanism, I provide reinforcing plates 102, riveted to the web 93 and partially surrounding the circular openings 111, which serve as bearings 90 for the tubular shafts. The web 93 is secured to the I-beams 40 and 44 by means of angle irons 101.

In Figs. 9 to 12 of the drawings I have shown the locking members comprising sheet 95 metal parts 91 and 92 and a separate plate 95, shown also in Fig. 3, extending throughout the width of the door, each of the locking members being secured to the plate 95. In Fig. 15 the block 5 and the part 92, which 100 form the bearings for the walls 3 and 4 are secured directly to the continuous side plate 95, the intermediate part 91, shown in Figs. 9 to 11 being omitted. In the form shown in Fig. 15 the part 92 and the plate 95 are 105 bent inwardly at the lower edge, as illustrated, in order to stiffen the structure at this point.

From the foregoing it will be apparent that I have provided simple and effective 110 means whereby any one or more of the drop doors may be opened and closed independently of the others, or whereby all of the doors of a single section may be dropped and closed simultaneously.

115 I claim:

1. In a car provided with a plurality of doors at each side of the longitudinal axis thereof, means comprising telescoping shafts extending to and operable from the end of 120 the car for opening any one of the doors independently of all the others.

2. In a car provided with a plurality of doors at each side of the center thereof, means extending to and operable from the end of the car for closing the doors in combination with means extending to and operable from the end of the car for opening any one of the doors independently of all the others.

3. In a car provided with a plurality of doors at each side of the longitudinal axis thereof, means comprising telescoping shafts extending to and operable from the end of the car for opening any one or more of the doors independently of all the others.
4. In a car provided with a plurality of doors at each side of the center thereof, means extending to and operable from the end of the car for closing the doors in combination with means extending to and operable from the end of the car for opening any one or more of the doors independently of all the others.
- 15 5. In a car provided with a plurality of doors at each side of the longitudinal axis thereof, means comprising telescoping shafts extending to and operable from the end of the car for locking and unlocking any one of said doors independently of all the others.
6. In a car provided with a plurality of doors at each side of the longitudinal axis thereof, means comprising telescoping shafts extending to and operable from the end of the car for unlocking any one or more of said doors independently of all the others.
7. In a car provided with a plurality of doors at each side of the center thereof, means for closing said doors, means independent of the door closing means for locking said doors in closed position, and means extending to and operable from the end of the car for locking and unlocking any one or more of said doors without operating the locking mechanism of the other doors.
8. In a car provided with a plurality of doors at each side of the center thereof, means for closing said doors, means independent of the door closing means for locking said doors in closed position, and means for unlocking any one or more of said doors without operating the locking mechanism of the other doors.
9. In a car provided with a plurality of doors, locking mechanism for each of the doors, a plurality of shafts extending from the end of the car to the respective doors, each shaft connected with the locking mechanism of its door.
- 50 10. In a car provided with a plurality of doors, locking mechanism for the doors, a plurality of telescoping tubular shafts, each shaft being connected with the locking mechanism of one of the doors.
- 55 11. In a car provided with a plurality of doors, locking mechanism for the doors, a plurality of telescoping tubular shafts extending longitudinally of the car, the largest shaft extending approximately to the inner edge of the door adjacent the end of the car and each of the other shafts projecting beyond the one next larger a distance approximately equal to the width of one of the doors, each shaft being connected to the locking mechanism of one of the doors.
12. In a car provided with a plurality of doors, telescoping tubular shafts connected with the operating mechanism of said doors.
13. In a car provided with a plurality of doors, a series of telescoping shafts, a crank upon each shaft, locks for the doors and connections between the cranks and the locks.
14. In a car provided with a plurality of dump doors, a separate lock for each door having a part adapted to engage the underside of said door, and mechanism beneath the car comprising telescoping shafts for operating each lock independently of all the others.
15. In a car provided with a dump door, a locking member pivoted above the door, and an anti-friction roll mounted on the locking member and spaced from the upper part of the locking member sufficiently to receive the edge of the door between said roll and said upper part of the locking member.
16. In a car provided with a dump door, a locking member for the door having an anti-friction roll adapted to bear upon the under side of the door, and a second anti-friction roll adapted to bear upon a fixed part of the car.
17. In a car, a dump door, a track provided with a notch on the under side thereof, a rocker arm for raising the door, the end of the arm engaging the notch when the door is in closed position.
18. In a car provided with a dump door, a rocker arm comprising two pivoted members provided with abutting surfaces, whereby the turning movement of the members upon the pivot is limited.
19. In a car provided with a dump door, a rocker arm comprising two pivoted members provided with abutting surfaces, whereby the arm remains rigid when the door is being raised but may yield upon the pivot when the rocker arm is lowered away from the door.
20. In a car provided with a dump door, a rocker arm, the end of which enters a depression in the door when the door is closed position, and means whereby the rocker arm may yield sufficiently to permit its end to recede from the depression when the rocker arm is lowered.
21. In a car provided with a dump door, a rocker arm, and a worm gear for operating the same to raise the door.
22. In a car, a center sill comprising two I-beams arranged with their central webs in the same vertical plane, and a reinforcing plate between the adjacent flanges thereof.
23. In a car, a center sill comprising two I-beams arranged with their central webs in the same vertical plane, a horizontal reinforcing plate between the adjacent flanges of the I-beams, the lower I-beam terminating

at the car bolsters and the reinforcing plate and the upper I-beam being continuous throughout the length of the car.

24. A transverse beam for a car, comprising a main web portion, reinforcing plates secured to the ends thereof, said reinforcing plates being spaced from the main web at their central portions and forming bearings for part of the door-locking mechanism.

10 25. A transverse beam for dump cars, comprising a main web portion and reinforcing plates at the ends thereof formed with projections adapted to co-act with the locking mechanism of the dump doors.

15 26. A transverse beam for a dump car, having a main web portion and reinforcing plates secured to the ends thereof, said reinforcing plates having outward projections adapted to support the locking mechanism 20 of the dump doors and having upward projections secured to the side stakes of the car.

27. A transverse beam for a dump car having a main web portion reinforced at its upper edge by angle irons, said angle irons 25 being spaced from the webs at the ends, and reinforcing plates secured to the ends of the web and extending upwardly and secured at their upper parts to the side stakes of the car.

30 28. A transverse beam for a dump car having a bearing opening therein for the door-operating shaft, and reinforcing plates secured to the opposite faces of the beam and extending partially around said opening.

35 29. In a dump car, locking mechanism for the doors, levers at the ends of the car for operating said locking mechanism and a plate substantially parallel to said levers when the doors are locked, and means for 40 locking said levers to said plate.

30. In a dump car, the combination of a plurality of load supporting doors, means

extending to and operable from the end of the car for independently releasing the doors, and common positive means for re- 45 locking the various doors.

31. In a dump car, the combination of a plurality of dumping doors on the same longitudinal side of the car, common means extending to and operable from the end of 50 the car for releasing all of them, and means for releasing any door from the action of the releasing mechanism.

32. In a dump car, the combination with a plurality of dumping doors on the same 55 longitudinal side of the car, means extending to and operable from the end of the car for releasing all of such doors together, and for releasing any door independently of the others.

33. In a car provided with a plurality of doors at each side and adjacent the center thereof, means comprising telescoping shafts extending to and operable from a single part 60 of the car for opening any one of the doors independently of all the others.

34. In a car provided with a plurality of doors at each side and adjacent the center thereof, means for closing all the doors from 70 a single part of the car in combination with means extending to and operable from a single part of the car for opening any one of the doors independently of all the others.

35. In a car provided with a dumping door, a series of locking members therefor 75 depending below the side walls of said car, and a vertical plate substantially in the plane of said side wall for rigidly connecting said members.

WILLIAM A. CASWELL.
